HOLDER FOR A SPOOL OF TAPE

Charles Castelli, New Brunswick, N.J., assignor to Johnson & Johnson, a corporation of New Jersey

Filed June 10, 1960, Ser. No. 60,912

Term of patent 14 years

(Cl. D58—26)

Fig. 1.

Fig. 3.

Fig. 2.

Fig. 4.

Fig. 5.

Fig. 6.

FIG. 1 is front elevational view of a holder for a spool of tape, showing my new design;

FIG. 2 is a rear elevational view thereof;

FIG. 3 is a front perspective view thereof;

FIG. 4 is a side elevational view taken from the right of FIG. 2;

FIG. 5 is a bottom plan view of FIG. 1; and

FIG. 6 is a top plan view of FIG. 1.

I claim:

The ornamental design for a holder for a spool of tape, as shown.
